UNITED STATES PATENT OFFICE.

JOHN FLAM, OF THE UNITED STATES ARMY, ASSIGNOR TO THE SECRETARY OF WAR
OF THE UNITED STATES OF AMERICA.

PERCUSSION-FUSE.

1,385,610.

Specification of Letters Patent. Patented July 26, 1921.

Application filed January 2, 1919. Serial No. 269,381.

(FILED UNDER THE ACT OF MARCH 3, 1883, 22 STAT. L., 625.)

To all whom it may concern:

Be it known that I, JOHN FLAM, private, Ordnance Department, United States Army, a citizen of the United States, stationed 5 at Washington, D. C., have invented an Improvement in Percussion-Fuses, of which the following is a specification.

The invention described herein may be used by the Government, or any of its officers 10 or employees in prosecution of work for the Government, or by any other person in the United States, without payment of any royalty thereon.

This invention relates to a useful improvement 15 in percussion fuses and more particularly to safety devices whereby the projectile can not be accidentally or prematurely exploded.

One object of my invention is to obtain a 20 maximum of simplicity and sturdiness of construction in a safety device that is positive in its action. By this means a material reduction in cost is obtained.

Another object of my invention is so to arrange 25 the safety means that before the shell encounters its objective there is a strong force constantly tending to separate the firing pin and primer, thus obtaining absolute safety.

Another object of my invention is to provide 30 a safety device that is compact and entirely inclosed within the shell.

My device may be applied to any of the well known types of shells arranged either 35 for immediate or delayed firing, to drop bombs released from airplanes, or to incendiary bombs.

The embodiment of my invention is illustrated 40 in the drawings in which:

Figure 1 is a longitudinal sectional view of the rear portion of the shell showing my safety device before the shell reaches its objective;

Fig. 2 is a similar view of the shell after 45 impact;

Fig. 3 is a sectional view on line 3—3 looking in the direction of the arrows; and

Fig. 4 is a side elevation of the firing pin and sprung disk.

Referring now more particularly to the drawings in which corresponding reference 50 characters refer to like parts throughout the views, the front casing 11 of the shell carries

an annular flange 12 near the rear. An internally threaded socket 13 is provided at 55 the rear end of the front casing 11. The cap 14 is of general bowl-shaped configuration, and is provided at its edge with the externally cut-threads 15 engaging with the internally threaded socket 13 of the front casing 11. Said end cap 14 carries a flange 16 having a smooth surface 17 parallel with the smooth surface 18 of the flange 12. The surfaces 17 and 18, and the thin peripheral area 19 form a narrow pocket when the end cap 60 14 is tightly screwed in place, for a purpose to be later described. At the center of the end cap 14 is the circular boss 20. The end cap 14 is also provided with a plurality of ribs 21, the tops of which are adapted to engage and support the sprung disk 22.

The sprung disk 22 carries at its center the firing pin 23 and weight 24. The weight 24 is guided in its forward movement by the edges of the ribs 21, so that the firing pin is 75 constrained to travel along the axis of the shell. The firing pin 23 has an integral collar 25 bearing against the front face of the disk 22, and a shank portion 26 extending through an aperture in the weight 24. The weight 24 and firing pin 23 are securely held to the disk 22 by means of riveting the shank 26 into the countersink provided at the rear of the weight 24. The weight 24 has a spherical portion 27 conforming to the shape 80 of the sprung disk 22 when said disk is thrown to its reverse position.

A primer 28 is arranged a short distance in front of the firing pin 23 and is adapted 85 to fire the shell when pierced by the firing pin 23. The charge 29 of the shell is held in place therein in any suitable fashion. The charge 29 and primer 28, as mentioned previously, may be arranged for immediate or delayed firing, or for incendiary effects. 90

The sprung disk 22 is so made that should it be straightened by a force acting therein, any additional strain produced thereon, no matter how small, will violently throw the disk 22 "over center" and it will assume the 100 reversed position shown in dot and dash lines. The sprung disk 22 is initially placed under a slight strain when the end cap 14 is screwed in place, and there is therefore a constant force acting against the boss 20 105 and the front surfaces of ribs 21.

The sprung disk 22 is made of sufficiently heavy spring steel so that any shock or jar incident to transportation or handling, such as that due to dropping the shell from a crane, will not be sufficient to throw the disk over center. When such a shock occurs, there is a tendency for the weight 24 and the firing pin 23 to keep going in the direction that the shell is dropped, due to the inertia possessed thereby, but the kinetic energy of the weight 24 and its associated parts is destroyed before the strain in the disk 22 is sufficient to cause it to snap over center. After the shock is over, the disk 22 immediately assumes the normal position shown in Fig. 1. It is evident from this explanation that a distinct advantage is gained by this construction, in that no matter how often the shocks may be repeated, the safety features cannot be impaired in function.

However, when the shell is actually fired, a very large amount of kinetic energy is imparted to the weight 24. The boss 20 and ribs 21 are provided so as to furnish a large bearing surface for the disk 22. Thus when the shell is in the bore of the gun and subjected to a tremendous accelerating force, the tendency for the disk 22 to be torn out of its pocket is overcome. Upon impact, the kinetic energy of the weight 24 is sufficient to carry the disk over center. As soon as this occurs, the disk immediately snaps into the position shown in Fig. 2, and the firing pin 23 is violently driven into the primer 28. Thus all that is necessary is to strain the sprung disk 22 sufficiently, and the construction of said disk itself will cause the proper movement of the firing pin. The actual firing, therefore, is not dependent directly upon the impact of the shell, said impact being utilized merely to release a

strong force for producing the desired relative movement of the firing pin and primer. The force for piercing the primer is not reduced by any spring arrangement that is so common with the ordinary type of fuse. 45

Since there is such a large difference between the kinetic energy imparted to the weight 24 when it is dropped even from an appreciable height, and when it is fired from a gun, no difficulty is experienced in designing the disk 22 so as to insure firing the shell when it reaches its objective. The entire device comprises, for all practical 50 purposes, a solid rigid structure, capable of being safely handled, or even repeatedly dropped from an appreciable height.

It is to be distinctly understood that my device may, if desired, be used in conjunction with any other safety means, for preventing accidental firing of the shell. The form shown is only one embodiment of my invention, and it is of course possible to reverse the arrangement shown by keeping the 55 firing pin stationary and having the primer movable.

Having now described my invention, what I claim as new and desire to secure by Letters Patent is:

In combination with a casing containing an explosive charge, a primer for igniting said charge, a cap secured to the casing and forming therewith an annular groove, guide ribs formed on the interior of said cap, a 70 spring plate having its periphery situated in the annular groove and slidable therein, a firing pin secured to the plate and normally held thereby in spaced relation to the primer and a weight secured to the firing pin for placing initial tension on the plate, said weight guided in its movement by the 75 guiding ribs.

JOHN FLAM.
